APPARATUS FOR SALVAGING VAPOR GAS FROM HYDROCARBON LIQUIDS

Manly E. Carroll, Sr., Manly E. Carroll, Jr., and Andrew G. Morgan, Hialeah, Fla., assignors to Senogas Corporation, Miami, Fla., a corporation of Delaware

Application July 23, 1954, Serial No. 445,348

3 Claims. (Cl. 183—25)

This invention relates to an apparatus for salvaging vapor gas from hydrocarbon liquids, and particularly to a device for continuously treating a flowing stream of hydrocarbon liquid fuel securing therefrom a vapor gas of substantially constant B.t.u. value as well as providing a liquid fuel with a substantially constant B.t.u. value.

In the manufacture of hydrocarbon fuels from petroleum, coal or the like, it is found that the various hydrocarbon liquid fuels, such as gasoline, benzine, benzol and the like, contain therein "slivers" of high volatile materials, such as butane, pentane and the like, which are substantially entrapped and carried by the liquid material.

These slivers of highly volatile materials readily vaporize upon contact with the atmosphere so that the agitation of the liquid during handling constantly brings a few of these slivers into contact with the atmosphere so that the handling, expansion or the like causes a constant evolution or loss of such material from the hydrocarbon fuels.

All users of hydrocarbon fuels, such as gasoline or the like, are well aware of the heavy fumes of hydrocarbon material which are liberated during the handling of the fuels. The ordinary user of gasoline, or other such hydrocarbon fuels, becomes so accustomed to the escape or loss of portions of his fuel into the atmosphere that little attention is paid thereto. However, it is apparent that valuable constituents of the hydrocarbon fuel are being lost by vaporization and dissipation to the atmosphere (the Government allows 2% loss for tax purposes), and not only are the fuel values being lost, but the presence of the highly volatile and frequently highly explosive vapors produces a fire and explosion hazard in the handling of such hydrocarbon fuels.

One of the annoying features of the high volatile materials in usual hydrocarbon fuels is so-called vapor lock. The high volatile material in the fuel being constantly under a tendency to vaporize, will vaporize under various undesirable conditions. For example, in a fuel pump, where suction is applied to the liquid fuel, the reduction in pressure may give the high volatile materials a chance to vaporize, in which case, they will occupy a much larger volume than while in the liquid phase, and only extreme pressures and low temperatures can cause these high volatiles to again condense to a liquid. Accumulation of these high volatile materials as a vapor may cause a break in the fuel column so that the pump will become inoperative to elevate the fuel from a tank to a discharge system. Further, should any portion of the liquid fuel system become slightly heated, the increase in temperature therein may produce volatilization of the high volatiles so that a fuel line may be blocked because of a quantity of vapor therein.

The tendency of these slivers of high volatile material to produce vapor lock has been extremely annoying in the aviation industry which has found it necessary to utilize high pressure fuel pumps with the fuel constantly under pressure to reduce the tendency to vapor lock. Further, it has been found necessary to introduce de-

2

vaporizing devices which constantly operate on the fuel in the aircraft storage system to remove the high volatiles therefrom and to discharge the same into the atmosphere. The presence of the high volatile materials not only produces dangerous operation of the motor system, but the discharge of the high volatiles introduces a fire hazard because of the extremely explosive nature of the high volatile air mixtures resulting.

Various attempts have been made to free these high volatile materials from the entraining liquids, either to stabilize the liquids or to provide the vapors as fuel material. Heretofore, considerable difficulty has been had in securing and utilizing these vaporous fuels because of the constant variation of the quality of the fuels produced. For example, it has been found that certain vapors can be produced by taking a quantity of hydrocarbon fuel, such as gasoline, benzine or the like, and containing it in a chamber and passing a stream of air therethrough to produce agitation of the liquid to liberate the slivers of high volatile materials contained therein. However, the gas produced by such method has been highly unsatisfactory in that the first gas produced is extremely rich in B.t.u. values with the quality rapidly decreasing from the beginning to the end of the treatment.

Also, various systems have been attempted utilizing high pressures or high temperatures or both to free the high volatile constituents from the entraining liquid. These processes have not only been found hazardous, but for the same reasons, the fuel produced has been unsatisfactory because of the varying quality thereof.

These high volatiles readily vaporize upon contact with the air or upon release of pressure, so that, when air is bubbled through the liquid, any sliver contacted by an air bubble will vaporize and be carried along by the air bubble, the remaining liquid being substantially freed of the high volatiles and may be handled without evolving excessive quantities of dangerous vapor.

The present invention relates to a system for treating hydrocarbon liquid fuels, such as gasoline and the like, to not only stabilize the liquid fuel by eliminating the high volatiles which heretofore have been evolved in random manner so that there was a constant fire and explosion hazard about the fuel, but also to utilize the fuel so recovered and to maintain the quality thereof at a substantially constant B.t.u. value so that the utilization thereof will be economical and satisfactory.

In the construction according to the invention, a plurality of generator or vapor evolving cells are provided with means for pumping a continuous stream of fuel from any suitable source thereinto and having the level of fuel in the evolving cell maintained by means of an exhaust pump which exhausts the stabilized liquid therefrom and returns it to suitable storage. Simultaneously, a quantity of air is passed through the cell by means of a diffuser having a plurality of apertures to produce streams of air bubbles upwardly through the contained liquid in the cell with the volume of air and the volume of fuel passing through the cell being regulated to produce a constant ratio of air to treated material so that the evolved vapor will be substantially constant in B.t.u. value.

A plurality of cells may be used so that the liquid fuel may be passed through one cell and treated with one ratio of air and then passed through a separate cell and treated with a separate or different ratio of air to produce two different types of vapor fuels. Each of these vapor fuels will have a substantially constant B.t.u. value, and may be used either independently or may be commingled to provide a vapor fuel having a B.t.u. value different from that of either of the evolved vapor fuels.

While this system may be used as a multiple pass for a single hydrocarbon fuel to completely stabilize

the same, it will usually be found that different liquids or different grades of the same liquid or same type of liquid will be passed through the various cells and the resultant hydrocarbon vapors may be utilized independently or together, as may be desired.

In the preferred construction according to the invention, first and second cells are provided together with a first and second supply pump and a first and second return pump, and interconnections provided between the various pumps and cells so that the liquids supplied to either or both cells may be determined at will from either of a plurality of sources and the resultant liquid either commingled or returned to separate tanks, as may be desired. The piping between the pumps and the cells being provided with various valves and cross-connections so that either pump may be operated to supply fuel to either cell from either of two independent sources or the return pump may be utilized to draw fuel from either of the cells and return it to the same or independent storage sources, means being provided so that the interconnections and pumps may be utilized at will.

It is accordingly an object of the invention to provide an improved method of stabilizing the B.t.u. value of hydrocarbon fuels.

It is a further object of the invention to salvage the high volatile components of hydrocarbon fuels.

It is a further object of the invention to provide a high volatile liberating system with means for interconnecting the system at will.

It is a further object of the invention to provide an improved high volatile evolving cell.

It is a still further object of the invention to provide an improved control system for a vapor evolving cell.

Other objects and many of the attendant advantages of the present invention will be apparent from the following detailed description taken in connection with the accompanying drawings in which:

Figure 1 is a perspective view of a vapor evolving system with the top portion cut away;

Figure 2 is a perspective view of a simplified modification according to the invention;

Figure 3 is a sectional elevation through a vapor evolving cell according to the invention;

Figure 4 is a top plan view of a refined modification according to the invention;

Figure 5 is a sectional elevation taken substantially on the plane indicated by the section line 5—5 of Figure 4 and showing the construction of the refined modification;

Figure 6 is a cross-sectional view through the refined modification taken substantially on the plane indicated by the section line 6—6 of Figure 5;

Figures 7, 8, 9 and 10 are perspective views of the top connection of the fuel stabilizer and the fuel salvage system according to the invention showing the different arrangements to secure the various flow paths therethrough;

Figures 11 to 82, inclusive, show the various valve settings to secure the various possible flow paths through the device, the various valves being arranged in the position and setting according to the flow path to be established in the various networks as illustrated in Figure 1;

Figure 83 illustrates the flow connections to the refined modification as indicated in Figures 4, 5 and 6.

In the construction of the device according to Figure 1, a first treating cell 10 and a second treating cell 12 are connected by means of suitable networks presently to be described to a first supply pump 14 and a second supply pump 16, and liquid fuel is exhausted from the cells by means of a first return pump 18 and a second return pump 20.

Each of the cells 10 and 12, as most clearly seen in Figure 3, is constructed as having a tubular body portion 22 having a bottom closure 24 which is preferably a supporting platform for the cells. A top 26 is secured

in fluid-tight relation to the body 22 and the bottom 24 is provided with an aperture 28 in which is screwed a drain pipe 30. The body 22 is provided with an aperture 32 intermediate the ends thereof and a supply conduit 34 is threaded into the body 22 and directed toward the bottom thereof. Likewise, the body 22 is provided with a return aperture 36 into which is threaded a return conduit 38. The return conduit 38 is preferably in the form of an L having a downturned goose-neck portion 40 extending into the body 22 and directed toward the bottom thereof. It is to be understood that various lengths of goose-neck 40 may be arranged to determine the depth of liquid fuel maintained within the body 22.

A diffuser head 42 is mounted in the bottom of the body 22 and preferably is provided with a rim 44 and a perforated top portion 46 having apertures 48 therein, while an air duct 50 is rigidly connected to the diffuser head 42 and preferably sealed in fluid-tight relation thereto. The area of the apertures 48 in the diffuser head 46 is preferably substantially 65% of the area of the bore 52 of the air duct 50. The top 26 is provided with an aperture 54 through which the air duct 50 extends and an upstanding collar 56 about the aperture 54 is threaded to receive the packing nut 58 to compress a packing gland 60 into fluid-tight relation with the side of the duct 50.

The top 26 is also provided with an aperture 62 through which extends a vapor passage 64 with the aperture 62 being surrounded by a collar 66 to receive a packing nut 68 to compress a packing 70 into sealing relation with the vapor passage 64. Top 26 may be secured to the body in any suitable way, herein shown as stud bolts 72 extending through the top 26 and screwed into the metal of the body 22.

The air ducts 50 of the first and second cells 10 and 12 are connected together by means of an air intake manifold 74 and the vapor passages 64 of the first and second cells 10 and 12 are connected together by means of an output manifold 76. Preferably, one of the manifolds 74 or 76 is offset by means of nipples 78 and 80 to provide a working space between the manifolds 74 and 76. An interconnecting duct 82 is provided between the manifolds 74 and 76 intermediate the ends thereof and provided with a control valve 81. The interconnecting duct 82 may be in offset formation as shown in Figure 2, or where space is not at too much of a premium, may be straight, as shown in Figures 7 to 10, inclusive.

An air intake duct 86 is connected to air intake manifold 74 between the junction of the cross-interconnect 82 and the air duct 50 of the second cell 12. A valve 88 is connected in the air intake manifold 74 between the junction of the interconnecting duct 82 and the air supply duct 86. Likewise, a valve 90 is placed in the air intake manifold 74 between the air supply duct 86 and the air duct 50 of the second cell 12.

A fuel output duct 92 is connected to the output manifold 76 intermediate the ends thereof. A valve 94 is placed between the vapor passage 64 of the first cell 10 and the output duct 92. Likewise, a valve 96 is interposed in the output duct 76 between the interconnecting duct 82 and the output duct 92.

Each of the valves 81, 88, 90, 94 and 96 is provided with an indicator handle 98 which, when turned transversely to the duct on which it is mounted, indicates that the valve is closed, and when it is extending longitudinally with the duct, indicates that the valve is open.

The manifolds 74 and 76 together with the interconnecting duct 82 and the air supply duct 86 and the output duct 92 together with the valves therein may be set up to provide a plurality of flow paths therein. For example, in Figure 7, with the valve 84 in the interconnecting duct 82 closed and the remaining valves open, the air will flow into each of the cells 10 and 12 through each of the air intakes 50 and the output vapor will flow through the vapor passages 64 and outwardly through the fuel duct 92.

Likewise, in Figure 8, with the valves 83 and 96 closed, the air will flow downwardly through the air intake duct 50 of the second cell 12 and outward through the manifold 76 to be blocked by the valve 96 and then across the interconnect 82 and downward into the air intake duct 50 of the first cell 10 and outwardly through the vapor passage 64 and through the valve 94 to the fuel duct 92. In this connection, it will be seen that the air flows in series through the generator cells so that the vapor having a given B.t.u. value is resaturated in one of the cells to secure a maximum carriage of fuel vapor and a different B.t.u. value.

In a valve set-up according to Figure 9, valves 83, 84 and 94 are closed so that the first cell 10 is completely cut off and vapor will only flow from the second cell 12. Likewise, in the modification of Figure 10, the second cell 12 is cut off and vapor will only flow from the first cell 10.

The fuel supply system comprises a supply pipe network having a first supply pipe 100 and a second supply pipe 102, a supply intake pipe 104 connected to the supply pipe 100 and to the intake port of the first supply pump 14 and the second supply intake pipe 108 connected to the intake port 110 of the second supply pump 16. A first supply pipe interconnect 112 is connected to the first supply pipe 100 by means of a T-connection 114 and may be connected at will to the intake pipe 108 by means of the valve C. A second supply pipe interconnect 116 is connected to the second supply pipe 102 by means of a T-connection 118 and a connection to the supply pipe 104 is controlled by means of the valve D. It will be apparent that the valves C or D may be opened or closed at will to provide suitable flow paths for the supply of fuel from any suitable storage tanks, not shown, to either or both of the supply pumps 14 and 16.

The output port 122 of the first supply pump 14 is connected to the supply conduit 34 of the first cell 10 by means of a supply tube 124. A flow regulating valve 126 is supplied in the fluid supply conduit 34 to control the rate of fluid flow therethrough. Each of the pumps 14, 16, 18 and 20 is provided with an internal relief passage so that excessive pressures cannot be built up in the pumps or the tubes connected thereto.

The second supply pump 16 has the output port 128 connected to the supply conduit 34 of the second cell 12 by means of a supply tube 130. A first cross-supply tube 132 is connected to the supply tube 124 by means of a three-way four-position valve A and connects to the supply tube 130 by means of a T 134. Likewise, a second cross-supply tube 136 is connected to the tube 130 by means of a three-way four-position valve B and connects to the tube 124 by means of the T-connection 138. It being apparent that by means of the valves A and B, the pumps may be connected directly to either of the cells 10 or 12 while either one of the pumps 14 or 16 may be connected to both cells, as may be desired.

Each of the return conduits 38 is provided with a throttle valve 140 to control the level of the liquid fuel within the cells 10 or 12, and a return network of tubes is connected to the return conduits 38 and to an input port 142 of the first return pump 18 and an input port 144 of the second return pump 20. The network comprises a first return tube 146 which connects the return conduit 38 of the first cell to the intake port 142 of the first return pump 18. And likewise, a second return tube 148 which connects the output conduit 38 of the second cell 12 to the input port 144 of the second return pump 20.

A first cross-return tube 150 is connected to the return tube 146 by means of the three-way four-position valve G and connected to the return tube 148 by means of the T-connection 152. Likewise, a second return cross-return tube 154 is connected to the return tube 148 by means of a three-way four-position valve H and is connected to

the return tube 146 by means of the T-connection 156. By this, it will be apparent that the return tubes may connect either or both of the first and second cells 10 and 12 to either or both of the return pumps 18 or 20 so that either pump 18 or 20 may pump from either cell or from both cells, or both pumps may pump from one cell or both cells, as the condition may require.

The discharge pipe network comprises a first discharge pipe 160 and a second discharge pipe 162 with a discharge pipe 164 extending from the output port 166 of the first output pump 18 and connecting to the discharge pipe 160 by means of the two-way angle valve F. Likewise, the output port 168 of the second output pump 20 is connected to the pipe 162 by a discharge pipe 170. The connection being made by the two-way angle valve E. It being apparent that either of the pumps 18 or 20 may be connected to either or both of the discharge pipes 160 or 162, as may be desired.

A first cross-discharge pipe 180 is connected to the discharge pipe 160 by means of a T 182 and flow from discharge pipe 170 is controlled by means of the angle valve E. A second cross-discharge pipe 184 is connected to the discharge pipe 162 by means of a T 186 and flow from pipe 164 is controlled by the two-way

25 three-position valve F. When both of the pumps 14 and 18 are out of use, a first clutch 174 may be disconnected to prevent the running of the pumps 14 and 18 and the consequent wear thereon. Likewise, if the pumps 16 and 20 are inoperative, the second clutch 176 may be disconnected to disconnect the pumps 16 and 20 from a driving motor 178. In the operation of the device according to the initial embodiment thereof, the supply pipes 100 and 102 will be connected to any suitable source of supply, preferably a different source. Likewise, the discharge pipes 160 and 162 will communicate with any suitable receiver which may be the same or different, as may be desired.

In the operation of the preferred commercial embodiment of the invention according to Figure 1, various valves A, B, C, D, E, F, G and H may be arranged to block the various pipes or to open the various cross-pipes in the networks so that a plurality of flow paths may be established to determine the particular operation of the device. For simplicity of illustration and description, the valves A, B, G and H have been indicated as T-valves or three-way four-position valves, while the valves C, D, E and F have been indicated as angle valves or three-position two-way valves. Obviously, these single valves could be replaced by normal valves of various kinds installed in the tubes themselves instead of being connected in the three-way position.

The various valve settings to determine the various flow paths and the flow paths established thereby are set forth in the following tabulation of the valve settings:

55

Flow path 1—Figure 11

Liquid fuel supply pipe 102 through second supply pump 16 to both cells; return from both cells to second return pump 20 and discharge through second discharge pipe 162

60 Valve C opens pipe 102 through pipe 108 to pump 16
Valve D closed

Valve A blocks tube 124 from pump 14

65 Valve B opens tube 130 and tube 136

Valve H opens tube 148 and cross-tube 154

Valve G blocks tube 146 to pump 18

Valve F closed

Valve E opens pump 20 through pipe 170 to pipe 162

70 Clutch 174 open

Clutch 176 closed

Flow path 2—Figure 12

Liquid fuel from supply pipe 102 through second supply pump 16 to second cell 12; return from cell 12 to

second return pump 20 and discharge through second discharge pipe 162

Valve C opens pipe 102 through pipe 108 to pump 16

Valve D closed

Valve A opens tube 124; blocks cross-tube 132

Valve B opens supply tube 130; blocks cross-tube 136

Valve H opens return tube 148; blocks cross-tube 154

Valve G blocks cross-tube 150

Valve F closed

Valve E opens pump 20 through pipe 170 to pipe 162

Clutch 174 open

Clutch 176 engaged

Flow path 3—Figure 13

Liquid fuel from supply pipe 102 through second supply pump 16 to first cell 10 and discharge through discharge pump 20 to second discharge pipe 162

Valve C opens pipe 102 through pipe 108 to pump 16

Valve D closed

Valve A blocks tube 124 from cell 10

Valve B blocks tube 130 to cell 12; opens cross-tube 136

Valve H blocks tube 148 from cell 12; opens cross-tube 154

Valve G blocks tube 146 from cell 10

Valve F closed

Valve E opens pump 20 through pipe 170 to pipe 162

Clutch 174 open

Clutch 176 engaged

Flow path 4—Figure 14

Liquid fuel from supply pipe 102 through first supply pump 14 to both cells and discharge through first return pump 18 to second discharge pipe 162

Valve C closed

Valve D opens pipe 102 through pipe 116 and 104 to pump 14

Valve A opens tube 124 and tube 132

Valve B blocks tube 130 to pump 16; opens tube 136

Valve H blocks tube 148 to pump 20; opens tube 154

Valve G opens tube 146 and tube 150

Valve F opens pump 18 through pipes 164 and 184 to pipe 162

Valve E closed

Clutch 174 engaged

Clutch 176 open

Flow path 5—Figure 15

Liquid fuel from supply pipe 102 through first supply pump 14 to cell 12 and return through return pump 18 to discharge pipe 162

Valve C closed

Valve D opens pipe 102 through pipes 116 and 104 to pump 14

Valve A blocks tube 124 to cell 10; opens cross-tube 132

Valve B blocks tube 130 to cell 12

Valve H blocks return tube 148 to cell 12

Valve G blocks return tube 146 to cell 10; opens cross-tube 150

Valve F opens pump 18 through pipe 164 and 184 to pipe 162

Valve E closed

Clutch 174 engaged

Clutch 176 open

Flow path 6—Figure 16

Liquid fuel from supply pipe 102 through supply pump 14 to cell 10 and return through return pump 18 to discharge pipe 162

Valve C closed

Valve D opens pipe 102 through pipes 116 and 104 to pump 14

Valve A opens tube 124 to cell 10; blocks tube 132

Valve B blocks tube 136

Valve H blocks tube 154

Valve G opens tube 146; blocks tube 150

Valve F connects pump 18 through pipe 164 and 184 to pipe 162

5 Valve E closed

Clutch 174 engaged

Clutch 176 open

Flow path 7—Figure 17

10 Liquid fuel from supply pipe 100 through supply pump 16 to both cells and return through return pump 20 to discharge pipe 160

Valve C opens pipe 100 through pipes 112 and 108 to pump 16

15 Valve D closed

Valve A blocks tube 124 to pump 14

Valve B opens tube 130; opens cross-tube 136

Valve H opens return tube 148; opens cross-tube 154

Valve G blocks return tube 146 to pump 18

20 Valve F closed

Valve E opens pump 20 through pipe 170 and 180 to pipe 160

Clutch 174 open

Clutch 176 engaged

Flow path 8—Figure 18

Liquid fuel from supply pipe 100 through supply pump 16 to cell 12 and return through return pump 20 to discharge pipe 160

Valve C opens pipe 100 through pipes 112 and 108 to pump 16

Valve D closed

Valve A blocks cross-tube 132

35 Valve B opens tube 130; blocks cross-tube 136

Valve H opens tube 148; blocks cross-tube 154

Valve G blocks cross-tube 150

Valve F closed

Valve E opens pump 20 through pipes 170 and 180 to pipe 160

40 Clutch 174 open

Clutch 176 engaged

35 In applications where a single fuel is to be fed to a single engine or group of engines, such as installations in vehicles or the like, it is possible to materially simplify the usual commercial installation by substantially eliminating the networks and a portion of the pump system and utilize a single supply pump connected to a single supply source and a single return pump. Such a construction is shown in Figure 2 wherein the cells 10 and 12 are shown mounted on a platform 200 which is installed in a cabinet-like device 202 with a driving pump 204 mounted on a subpanel 206 with fluid supply conduit 208 extending out to a union 210 at the exterior of the cabinet 202 and connected to a supply pump 212 coupled directly to the motor 204 by means of a suitable coupling 214 and delivering fluids through a supply tube 216 having a branch 218 and a branch 220, each of which is controlled by means of a suitable throttle valve 175 to determine the flow of liquid hydrocarbon fuel into the tanks 10 and 12 and having a return branch 222 from tank 10 and a return branch 224 from tank 12 connecting to a return line 226 which, in turn, is operated by means of a return pump 230 delivering the stabilized fuel to the discharge line 232 having a coupling 234 exterior of the cabinet.

40 Each of the tanks 10 and 12 is provided with a sight gauge 240 which has been omitted from the remaining figures for purposes of simplicity. Also, the tanks 10 and 12 may be provided with housings 242 to contain liquid level operated switches of any conventional character (not shown) so that upon a predetermined depth of liquid material in the tanks 10 or 12, the switches will be operated either to shut down the equipment or to give suitable alarms or to take any other action which may be needed. For purposes of simplicity, the switch housings 242 have been omitted from certain of the drawings, but it will be understood that each of the cells 10 and 12 will be provided with such switches. Obviously, the vapor and air duct network will be identical in each of the modifications so that vapor may be delivered or resaturated as may be desired.

45 In certain applications, it is desirable to have a maximum control over the quality of the salvaged fuel as well as over the control of the flow of the liquid fuel, and for this purpose, a refined modification cell has been provided, as illustrated in Figures 4, 5 and 6, which may be substituted for the cells 10 and 12 in any of the modifications.

A de luxe cell according to this modification is preferably of substantially rectangular tubular formation having a main body 250 mounted on a base 252 which is the top member of a hollow base having a bottom 254 and ends 256 and 258. An aperture 260 is provided in the bottom of the cell, and a drain tube 262 is connected therein and provided with a control valve 264. A liquid fuel intake aperture 266 has connected thereto the supply conduit 270 which may be controlled by means of a flow regulator valve 272. Inlet tube 274 may be either the supply tubes 124 or 130 of the previously disclosed embodiment.

A return conduit 276 is connected into an aperture 277 which is between the bottom of the cell and the input aperture 266. The flow through the return conduit 276 will likewise preferably be controlled by means of a flow regulator valve 278.

The normal level control in the de luxe cell will be by means of a standpipe 280 connected in an aperture 282 in the plate 252 in the bottom of the cell and communicating with a return tube 284 which is connected with return tube 276 by a suitable connection and which may connect to any desired return tube, such as the return tube 146 and 148 of the other embodiment or to the return tube 226 of the simplified construction.

A diffuser head 286 is likewise substantially rectangular and is supplied by a duct 288 which extends through an aperture 290 and has the supply air manifold 292 connected thereto. An aperture 294 will be supplied adjacent the top portion of the body 250 and a liquid level responsive switch of any conventional character 296 will be communicated to the interior of the body 250 through the aperture 294.

A drying cell comprises a body 300 which is substantially a duplicate of the body 250 and is also mounted on the plate 252 and provided with a drain aperture 302 into which a drain tube 304 is connected and preferably controlled by means of a valve 306 with the drain tubes 262 and 304 being connected to a drain pipe 308 which preferably extends through an aperture 310 in the base member. Obviously, through the use of the valves 264 and 278 there is provided similarly controlled drain portions optionally usable depending upon the piping installation being utilized.

A vapor port 312 in the body 250 is communicated with a vapor port 314 in the body 300 by means of a passage constituted by a slanting bottom portion 316. A cover 320 extends over both of the bodies and forms a top closure for the vapor passage as well as a top closure for the bodies 250 and 300. A baffle 322 is connected to the top 320 by means of a slanting portion 324 and extends downwardly in proximity to the baffle 322 so that the vapor passing from the body 250 must make sharp right angular bends so that droplets of liquid fuel carried by the vapor will be thrown out. Also, the cell 300 provides a space in which the vapor may readily expand and become substantially stagnant so that any droplets carried thereby will readily fall therefrom.

A vapor outlet 326 is connected to an outlet manifold 328. The manifolds 292 and 328 may well be the manifolds 74 and 76 of the other modification. An air supply duct 330 will correspond to the air supply duct 86 and the vapor fuel conduit 332 will correspond to the vapor duct 92.

These so-called "de luxe" cells may be substituted for the normal cells 10 and 12 in any place where it is desired to have a particularly dry fuel or where for other purposes it is desired to particularly control the flow of fuel.

In the utilization of the standpipe, it is desirable to provide the standpipe 280 with a measured orifice 336 so that the flow of fuel through the standpipe 280 may be readily controlled and preferably will be so regulated that the valve 278 will be maintained closed and flow will be regulated by the orifice 336 of the standpipe 280.

Obviously, various standpipes 280 may be utilized, either having various lengths or various sized orifices 336 so that the quantity of liquid fuel on the top of the diffuser 286 may be readily controlled.

5. For purposes of exemplification, particular embodiments of the invention have been shown and described according to the best present understanding thereof. However, it will be obvious to those skilled in the art that various changes and modifications in the construction and arrangement of the parts thereof may be readily resorted to without departing from the true spirit and scope of the invention.

What is claimed as new is as follows:

1. A vapor fuel generator comprising a separator cell 15 including a hollow body, a top and a bottom member applied to said body, said body having an inlet aperture intermediate the ends thereof, a liquid inlet conduit communicating with said inlet aperture, an outlet aperture in spaced relation from the bottom of said body, said 20 outlet aperture being intermediate between said inlet aperture and the bottom of said body, a liquid return conduit communicated with said outlet aperture, a diffuser head mounted in the bottom of said body, means including an air duct communicated with said diffuser head for passing air into and through the flowing liquid fuel in said body at a fixed ratio by volume of fuel to air, a vapor passage communicated with said body adjacent the top thereof, a drying cell including an elongated chamber, a vertically disposed baffle sealed to the top and sides of 25 said chamber, said vapor passage communicating with said chamber adjacent the top thereof and at one side of said baffle, a vapor fuel outlet conduit communicated with said chamber adjacent the top thereof and at the other side of said baffle, a liquid level switch mounted adjacent 30 the top of said body, a standpipe extending upwardly through the bottom of said body and terminating in spaced relation from the bottom of said body said standpipe being connected to said liquid return conduit, and a valve in said liquid return conduit between said outlet 35 aperture and said standpipe.

2. A vapor fuel generator comprising a separator cell including a hollow body, a top and a bottom member in said body, said bottom member having a drain aperture therein, a closure in said drain aperture, said body having an inlet aperture intermediate the ends thereof, a liquid inlet conduit communicating with said inlet aperture, an outlet aperture in spaced relation from the bottom of said body, said outlet aperture being intermediate 45 said inlet aperture and the bottom of said body, a liquid return conduit communicated with said outlet aperture, a diffuser head mounted in the bottom of said body, means including an air duct communicated with said diffuser head for passing air into and through the flowing liquid fuel in said body at a fixed ratio by volume of fuel to air, a vapor passage communicated with said body adjacent the top thereof, a drying cell including a chamber, a vertically disposed baffle sealed to the top and sides of 50 said chamber, said baffle terminating in spaced relation to the bottom of said chamber, said vapor passage communicating with said chamber adjacent the top thereof and at one side of said baffle, a vapor fuel outlet conduit communicated with said chamber adjacent the top thereof and at the other side of said baffle, a standpipe extending upwardly through the bottom of said body and terminating in spaced relation from the bottom of said body, said standpipe being connected to said liquid return conduit, a valve in said liquid return conduit between said outlet aperture and said standpipe, said chamber having a drain opening in the bottom thereof, a closure 55 applied to said drain opening, and a common drain pipe connected to said drain opening in said chamber and said drain aperture in said body.

3. A vapor fuel generator comprising a separator cell including a hollow body, a bottom member having a drain aperture therein, a closure in said drain aperture, said

body having an inlet aperture intermediate the ends thereof, a liquid inlet conduit communicating with said inlet aperture, an outlet aperture in spaced relation from the bottom of said body, said outlet aperture being intermediate said inlet aperture and the bottom of said body, a liquid return conduit communicated with said outlet aperture, a diffuser head mounted in the bottom of said body, a top member, means including an air duct extending through said top member and communicated with said diffuser head for passing air into and through the flowing liquid fuel in said body at a fixed ratio by volume of fuel to air, a vapor passage communicated with said body adjacent the top thereof, a drying cell including a chamber, a vertically disposed baffle sealed to the top and sides of said chamber, said baffle terminating in spaced relation to the bottom of said chamber, said vapor passage communicating with said chamber adjacent the top thereof and at one side of said baffle, a vapor fuel outlet conduit communicated with said chamber adjacent

5

the top thereof and at the other side of said baffle, said chamber having a drain opening in the bottom thereof, a closure applied to said drain opening, and a common drain pipe connected to said drain opening in said chamber and said drain aperture in said body.
